MOBILE WEIGHING UNIT FOR BULK MATERIALS

James M. Smith, Golden, Colo., assignor, by mesne assignments, to The Great Western Sugar Company, Denver, Colo.

Filed May 20, 1968, Ser. No. 11,999

Term of patent 14 years

Int. Cl. D12—10, 13; D10—99
U.S. Cl. D14—3

FIG. 1.

FIG. 2.

FIG. 3.

FIG. 4.

FIGURE 1 is a side view in elevation of a mobile weighing unit for bulk materials showing my new design;

FIGURE 2 is a top view thereof;

FIGURE 3 is a front view in elevation; and,

FIGURE 4 is a rear view in elevation thereof.

The other side view is substantially a mirror image of that shown in FIGURE 1.

I claim:

The ornamental design for a mobile weighing unit for bulk materials, as shown and described.
